Primary Examiner — Kevin Rudzinski*Assistant Examiner* — Sean D Lough(74) *Attorney, Agent, or Firm* — Brooks Acordia IP Law, PC(57) **CLAIM**

The ornamental design for a twilight light box, as shown and described.

DESCRIPTION

FIG. 1 is a perspective view of a twilight light box showing our new design;

FIG. 2 is a right side elevational view of the embodiment of FIG. 1;

FIG. 3 is a left side elevational view of the embodiment of FIG. 1;

FIG. 4 is a front elevational view of the embodiment of FIG. 1;

FIG. 5 is a rear elevational view of the embodiment of FIG. 1;

FIG. 6 is top plan view of the embodiment of FIG. 1; and, FIG. 7 is a bottom plan view of the embodiment of FIG. 1. Surface shading is used to shade FIGS. 1-7 to show clearly the character and contour of all surfaces of the 3-dimensional aspects of the design. The broken lines (where present) in all FIG. views illustrate portions of the twilight light box as environment that forms no part of the claimed design.
